SEVERING MACHINE FOR FORMING
TUFTED FABRICS

Frank William Riddle, Biscoe, N. C., assignor to
Aileen Mills Company, Biscoe, N. C., a corpora-
tion of Delaware

Application January 9, 1951, Serial No. 205,101

10 Claims. (Cl. 139—291)

1

This invention relates to improvements in apparatus and methods for making tufted fabrics, and more particularly to the severing of continuous tuft cords, employed in the manufacture of such fabrics, after weaving of the cords into the fabric.

It is a common expedient in the manufacture of fabrics of this character to feed continuous tuft cords, each comprising a bundle of threads, in parallel relation and in the direction of and above the warp threads of the fabric. By suitable manipulation of the loom harness, controlled by the feeding of an appropriate pattern to the loom dobby or the like, the tuft cords are depressed at intervals, together with selected warp threads, to provide a shed for the passage of the shuttle, whereby the cords are woven into the fabric at spaced points in the length thereof. Intermediate these points the cords are free, constituting loops, and the loops thus formed in the cords are disposed in rows, generally aligned transversely of the fabric. Tufts are then formed by severing the loops, thereby forming the tuft ends.

This is a conventional operation, commonly performed on ordinary power looms, the cutting of the tuft loops being effected manually by moving a cutting tool across the fabric to sever the aligned loops, one transverse row of loops being cut on each stroke of the tool. It is a feature of the instant invention that the cutting is effected automatically and in such a manner as to provide greater accuracy in the cutting and increased uniformity in the length of the tufts.

It is, therefore, an object of the invention to provide apparatus, either as a component of a loom, or as an attachment for or an adjunct to a loom, whereby tuft cords woven at intervals into a fabric so as to provide tuft loops, may be severed substantially midway of each loop, in combination with means whereby such apparatus is operated automatically and in timed relation to the lengthwise advance of the fabric.

More specifically, it is an object of the invention to provide, in a loom suitable for use in the manufacture of tufted fabrics, a cutting device reciprocable transversely of the fabric and in timed relation to the operation of the loom, to effect cutting of successive rows of aligned loops on each transverse stroke in either direction of the cutting device.

As the result of the action of the temples, which apply transverse tension to the woven fabric, the weft threads are usually curved rearwardly to some extent adjacent the selvage, and

2

there is corresponding rearward displacement at each side of the fabric of the points at which the tuft cords are woven into the fabric. Thus the tuft loops are not precisely aligned in each transverse row, and cannot be severed by transverse motion of a cutting device in a straight line.

The present construction is such that substantial displacement of the cutting elements fore and aft of the fabric is permitted during the transverse stroke, whereby this distortion of the fabric is compensated, the cutting elements being caused to follow the transverse rows of tufts from one edge of the fabric to the other.

In my prior application, Serial No. 134,554, filed December 22, 1949, I have described a method of controlling the transverse movement of the cutting device so as to prevent the application of undue strain to the fabric during the cutting of tuft loops adjacent the selvage.

The present invention contemplates a simplified method of achieving this result, involving the employment of two cutting elements, the cutting stroke being initiated at one selvage and proceeding to the opposite selvage, the severing of the several tuft loops adjacent the selvage at the beginning of each cutting stroke being prevented by the structure of the cutting device and by terminating each cutting stroke before the cutting device has moved beyond the selvage.

As will be hereinafter more fully explained, several tuft loops at alternate sides of the fabric and in adjacent transverse rows are left uncut by the first cutting element, but are severed on the succeeding cutting stroke by the second cutting element. By the employment of this method less frequent reversal of the driving motor is required and more uniform cutting results.

It is a further feature of the instant invention that the length of the cutting unit, measured in the direction of travel of the fabric, is substantially shortened so as to permit the mounting of the motor above the usual breast beam of the loom, whereby the apparatus requires substantially less clearance in front of the loom than was needed for the apparatus of the earlier application.

Further features and objects of the invention will be apparent from the following description, taken in connection with the accompanying drawings, in which:

Figure 1 is a fragmentary plan view of part of a loom illustrating one mode of practicing the invention;

Figure 2 is a front elevation of the loom shown in plan in Figure 1;

Figure 3 is a vertical section taken on the line 3—3 of Figure 2;

Figure 4 is a sectional view on the line 4—4 of Figure 3;

Figure 5 is a sectional view of a detail taken substantially on the line 5—5 of Figure 1;

Figure 6 is a front elevation of reduction gearing employed to traverse the cutting device;

Figure 7 is a horizontal section on the line 7—7 of Figure 3;

Figure 8 is a vertical transverse section on the line 8—8 of Figure 7; and

Figure 9 is a wiring diagram suitable for controlling the operation of the claimed apparatus.

In order to promote an understanding of the invention, a preferred embodiment thereof is illustrated in the drawings and specific language is used to describe the same. It will be understood, however, that further modifications and alterations of the illustrated structure are contemplated, such as would normally occur to one skilled in the art, and that the descriptive language is not to be construed as limiting the scope of the invention.

The invention is illustrated as applied to a conventional type of dobby loom, the details of which form no part of the instant invention, but may be varied widely. Thus the warp threads 18, carried on a beam at the rear of the loom, are fed forwardly through a reed 15, and are raised and lowered by harness 16 which is controlled by jacks 17, the latter being selectively rendered operable by a pattern chain 20, fed through a dobby 21. The cloth or fabric 24 is passed over a roughened roll 25 and wound on a cloth roll 26, temples 28 being provided at each side of the fabric to apply transverse tension to the latter in the known manner. A loom of generally similar type and mode of operation is shown in the patent to Cobb 1,383,076, in which the pattern chain is of the type in which pins are selectively inserted to control the operation of the jacks, and thereby the harness.

As hereinbefore indicated, the invention is concerned with the production of tufted fabrics which are formed by weaving into the fabric tuft cords or ropes, each comprising a considerable number of threads. The cords are woven into the fabric at spaced intervals, thereby forming tuft loops, which are severed, leaving the free ends or tufts. Thus as shown in Figures 1 and 3, tuft cords 30 are fed forwardly over and in the general direction of the warp threads 18. By lowering the tuft cords 30 at intervals, each cord is woven into the fabric at spaced points 33, forming a free loop 34 intermediate these points. Since all of the tuft cords are lowered and woven in at the same instants, adjacent loops are substantially aligned, although some distortion of the fabric, and resultant rearward displacement (in a direction opposite to the direction of advance of the fabric) of the loops occurs adjacent the selvage, as the result of lateral tension applied to the fabric by temples 28. Thus in order to cut the tuft loops, a substantially straight cutting stroke may be taken across the fabric and over the major portion of the width of the fabric, but as the cutting elements approach the selvage, they must be allowed to move rearwardly to compensate for the lack of alignment of the loops at either side of the fabric. The manufacture of tufted fabrics in this manner, the cutting of the tuft loops being performed manually, is a well

known practice. In accordance with the instant invention, the severing of the tuft loops, formed in the usual way, is effected by automatic mechanism about to be described, embodying the inventive concept.

The automatic mechanism, which may be considered either as an attachment or an adjunct to a conventional loom, is located, with the exception of certain control switches, at the front of the loom and may be mounted on a structural part 35 of the loom frame, sometimes called the "breast beam," as shown in Figures 1 and 2.

Thus a guide plate 36 and a stationary rack 60, bolted to the guide plate, are secured rigidly to the breast beam of the loom by bolts 37, which extend through aligned apertures in the guide plate and are received in corresponding threaded apertures formed in the breast plate, suitable spacers 38 surrounding the bolts 37 and being interposed between the forward face of the breast plate and the guide plate 36 to position the latter.

A drive unit comprising an electric motor 50 is mounted in annular collars 48, and a gear housing 51 abuts one of these collars, the housing and collars being secured together by bolts 49 extending through apertures in the same, spacers surrounding the portion of the bolts intermediate the two collars 48.

Within the gear housing 51 is a train of reduction gearing, shown more particularly in Figure 6, which serves to transmit toward torque at reduced speed from the motor to a driven shaft 71 which is suitably journaled in the housing and extends exteriorly thereof. Thus, motor shaft 67 extends into housing 51 and carries a pinion 68, the latter driving a gear 70 secured to shaft 71 through a train of three double idler gears 69, each idler gear having a driven toothed portion of relatively large diameter and a driving toothed portion of small diameter, as is conventional in reducing spur gearing trains. Secured to the outer end of shaft 71, and disposed exteriorly of housing 51, is a gear 72 which meshes with a mating gear 73. Gear 73 and pinion 74 are mounted on a common stub shaft 64, which is suitably journaled in a casting or bracket 65, the latter being bolted to the collars 48, and thus secured rigidly to motor 50.

Bracket 65 is provided with a vertical depending flange 66 disposed in parallelism with and adjacent to guide plate 36. Flanged rollers 53 are journaled in bracket 65 and are interlocked with the upper and lower edges of guide plate 36, so that bracket 65 and the entire drive unit are so supported on the guide plate as to roll on the latter transversely of the loom. It will be appreciated that on energization of the motor 50, the pinion 74 is driven from the motor and reacts against the stationary rack 60 to propel the drive unit across the loom.

Secured to the annular collar 48 is a bracket 52 which supports, adjacent the rearward end of the drive unit, a bearing block 78. Slidably mounted in block 78 is a bearing 81 for a spindle 83, and mounted on spindle 83 is a pair of circular cutting blades 80 and 85. A pulley 84 is also mounted on spindle 83, intermediate the cutting blades, the structure being shown more particularly in Figures 7 and 8.

The lower part of the cutting edge of each of the blades 80 and 85 projects into a slot 86 in an elongated shoe 88. The shoes 88 are secured rigidly to the underside of bearing 81, so as to partake of sliding movement with the

bearing in its bearing block 78. Thus the structure which is supported by bearing 81, including shoes 88 and blades 80 and 85, is displaceable as a unit in a fore and aft direction. Each of the shoes 88 is narrowed or curved at each end so as to facilitate the passage of the shoes between the tuft loops 34 and the fabric 24, as illustrated in Figure 1, the shoes resting on the fabric. Thus as the motor 50, gear housing 51, cutting blades 80 and 85 and other parts moving therewith, all of which may, for convenience, be termed the cutting device, are reciprocated on guide plate 36 as hereinbefore described, the shoes 88 traverse the fabric passing under the tuft loops 34 in succession. The spacing between the shoes 88, measured lengthwise of the fabric, is such that during such traverse the shoes intersect tuft loops in adjacent transverse rows. During reciprocation of the cutting device, the cutting blades 80 and 85 are rapidly rotated by means of a belt 76 which drivingly connects pulley 84 with a pulley 77 on the motor shaft 67, so that the blades readily sever the tuft loops as the shoes 88 pass beneath the same.

As is hereinbefore pointed out, the transverse rows of tuft loops tend to curve rearwardly at either side as the result of the distortion of the fabric adjacent the selvage. This irregularity in the alignment of the tuft loops in a transverse direction is compensated by movement fore and aft of the bearing 81 in the bearing block 78. The bearing 81 is urged toward the rearward end of the bearing block 78 by lever 90, which is pivoted intermediate its ends to bracket 52 at 87, and is provided at its lower end with an aperture receiving a stud 91 which projects laterally of the bearing 81 through an elongated slot 79 in block 78, the lever being biased to apply a normal thrust rearwardly to the bearing 81 by means of a coil spring 89, secured at its ends to the upper end of lever 90 and the forward collar 48. Thus when the shoes 88 rest on the fabric near either selvage, the bearing 81 is displaced, and with it the shoes 88 and the cutting knives 80 and 85, to the rearmost position in the bearing block 78 by the action of the spring 89. As the cutting device traverses the fabric, and approaches the central, undistorted portion, the shoes 88 are caused to follow the direction of the transverse rows of tuft loops, and the bearing 81 is displaced forwardly in the block 78, against the action of the coil spring 89. The range of displacement of bearing 81, and the position assumed by the bearing when the cutting device has reached the end of the cutting stroke and the shoes 88 are no longer confined by tuft loops, are determined, of course, by the length of the slot 79 in block 78.

A simple means and method of controlling the reciprocating movement of the cutting device is represented diagrammatically in Figure 9 of the drawing. Thus motor 50 is of any conventional reversible type, energized from a supply line 93 through either of the conductors 94 and 95, for the purpose of rotating the motor in opposite directions, conductor 96 being common to both circuits, and being directly connected to one side of the supply line. Conductors 94 and 95 are selectively connected with the other side of the supply line upon energization of relays 98 and 99 respectively. One end of the winding of each of these relays is connected to the same side of the supply line; the other ends of each winding are connected to the other side of the supply line through a single throw switch,

switch B being connected in series with the winding of relay 98 and switch D being connected in series with the winding of relay 99. The switches are normally biased to the open positions in which they are shown in Figure 9.

Switches B and D are mounted on the loom frame below the dobby 21, switch B and its operating arm 105 being shown in Figure 2 of the drawing. The operating arm of each of switches B and D is positioned for operation by a separate jack 17; the jacks selected for this purpose are a pair which are not being used for the manipulation of loom harness. Either of switches B and D may thus be operated at selected intervals by the insertion in the pattern chain of pins for controlling the operation of the jacks by which the switches are respectively operated.

Thus, referring again to Figure 9, motor 50 may be energized to displace the cutting device to the right by closing switch D, to energize relay 99 and complete the motor circuit through conductor 95. The closing of switch B will energize relay 98, and current will be supplied through conductor 94 to drive the motor in the reverse direction, the cutting device moving to the left. Starting and stopping, as well as control of direction of reciprocation, may thus be effected by operation of either of the switches B and D in accordance with the setting of the pattern chain.

At the end of each cutting stroke, travel of the cutting device across the loom is terminated by a bumper, one being mounted on each end of guide plate 36, as shown in Figure 1. Thus, as shown more particularly in Figure 5, each bumper comprises a barrel 61 bolted to the adjacent end of the guide plate 36, in which is slidably received a plunger 62. A coil spring 63, seated in an enlarged portion of the recess 55 in the barrel, engages a shoulder 58 on the plunger to normally urge the latter in one direction, rotation of the plunger in the barrel being prevented, if desired, by a laterally projecting pin 57 which rides in a longitudinal slot 59 formed in one side of the barrel. As the cutting device reaches either terminal position, the plunger 62 is engaged by a part of bracket 65, the plunger yielding to reduce the shock on impact. The lateral position of the bumpers is such that in each terminal position of the cutting device, the cutting knives have just passed over the tuft cord directly adjacent the selvage edge, but the shoes 88 extend inwardly sufficiently far to overlie the three or four tuft cords adjacent that edge.

The operation of switches B and D to cut the tuft loops in the preferred manner, and particularly in such a way that tuft loops adjacent either side of the fabric are invariably cut by displacement of the cutting device toward the selvage, so as to avoid placing undue strain on the fabric, may be effected as follows. Assuming that the cutting device initially occupies a position such that the shoes 88 are at the left-hand side of the fabric, as shown in Figure 1, the motor 50 may be energized, through the feeding of the pattern chain, by the closing of switch D. The cutting device is thus caused to move to the right across the entire fabric until the shoes 88 occupy a corresponding position adjacent the right-hand selvage. During this initial cutting stroke, tuft loops in two adjacent transverse rows are cut by the respective knives 80 and 85. As the cutting device approaches the right-hand terminal position, switch D is opened by the pat-

tern chain, and displacement of the cutting device is terminated to the bumper device shown in Figure 5. The cutting device remains stationary until the fabric has advanced sufficiently to bring into alignment with the rearward shoe 88 the next adjacent transverse row of tuft loops. Switch B is then closed, and the cutting device moves to the left until it reaches a position adjacent the left-hand selvage, switch B being opened by the pattern chain as the terminal position is approached, and movement of the cutting device being terminated by engagement with the left-hand bumper. During this cutting stroke, the rearward knife 80 will cut all of the tuft loops which it intersects except the three or four loops adjacent the left-hand selvage; the associated shoe 88 overlies these loops, which have been advanced beneath the shoe, and which are, therefore, not engaged by the knife. The forward knife 85 will intersect, during this cutting stroke, tuft loops which have already been cut until the last few tuft cords are reached, and these will be severed by knife 85. When the fabric has advanced through a distance corresponding to the spacing between adjacent transverse rows of tuft loops, switch D will again be closed to effect displacement of the cutting device to the right until the right-hand terminal position is reached. During this cutting stroke, the rearward knife 80 will cut all of the tuft loops which it intersects except the first three or four loops adjacent the right-hand selvage, which lie under the shoe 88; forward knife 85 will cut only the loops in the several cords adjacent the right-hand selvage which were not cut during displacement of the cutting device on the previous cutting stroke.

It will be appreciated, therefore, that each cutting operation except the initial one is begun at a point inwardly of the selvage to minimize strain on the fabric, that on each cutting stroke the forward knife cuts all of the cords except the few adjacent the selvage from which the cutting stroke proceeds, while the rearward knife cuts only the few cords adjacent the far selvage which have been left uncut on the preceding cutting stroke. This mode of operation is simpler in several respects than that proposed in my prior application, which employed only one knife or cutting element.

As in the apparatus shown in my prior application, the mounting of the driving motor on the traveling cutting device affords a convenient method of rotating the cutting blade at a relatively high speed, and traversing the cutting device at a relatively low speed, from a common power source and with the least structural complication. It will be appreciated, however, that in its broader aspect the invention is not limited to this preferred embodiment, but envisions various other means and provisions for propelling the cutting device and manipulating the blade, such as would occur to those skilled in the field to which the invention relates. Similarly, other control systems, operable in timed relation to the rate of feed of the fabric, may be substituted for that illustrated and described herein.

Having thus described the invention, what is claimed as new and desired to be secured by Letters Patent is:

1. An attachment for a loom on which is woven a fabric having tuft cords extending lengthwise of the fabric, said cords being woven in the fabric at spaced intervals in the length of the fabric so as to provide tuft loops, the loops in adjacent

5 cords being substantially aligned transversely of the fabric, said attachment comprising, in combination, guide means mounted on the loom and extending across the fabric, a cutting device mounted on said guide means for reciprocation lengthwise of said guide means and across said loops to engage and sever the latter, said cutting device comprising a pair of rotatable cutting blades positioned to engage and sever concurrently loops in adjacent transverse rows of loops, 10 a motor for rotating said blades, and an operative driving connection between said motor and said guide means to propel said cutting device lengthwise of said guide means in one direction, and, after advance of the fabric through a distance corresponding to the spacing between adjacent rows of tuft loops, to propel said cutting device lengthwise of said guide means in the other direction, and means operable in timed relation with said loom for energizing said motor to effect reciprocation of said cutting device on said guide means, whereby said loops are successively engaged and severed by said cutting blades on movement of said cutting device across the fabric in each direction to form the tufts.

2. An attachment for a loom on which is woven a fabric having tuft cords extending lengthwise of the fabric, said cords being woven in the fabric at spaced intervals in the length of the fabric so as to provide tuft loops, the loops in adjacent cords being substantially aligned transversely of the fabric, said attachment comprising, in combination, guide means mounted on the loom and extending across the fabric, a cutting device mounted on said guide means for reciprocation lengthwise of said guide means and across said loops to engage and sever the latter, said cutting device comprising a pair of cutting blades spaced lengthwise of said fabric by substantially the distance between adjacent transverse rows of tuft loops, a motor, and an operative driving connection between said motor and said guide means to propel said cutting device lengthwise of said guide means in one direction, and, after advance of the fabric through a distance corresponding to the spacing between adjacent rows of tuft loops, to propel said cutting device lengthwise of said guide means in the other direction, and means operable in timed relation with said loom for energizing said motor to effect reciprocation of said cutting device on said guide means, whereby said loops are successively engaged and severed by said cutting blades on movement of said cutting device across the fabric in each direction to form the tufts.

3. An attachment for a loom on which is woven a fabric having tuft cords extending lengthwise of the fabric, said cords being woven in the fabric at spaced intervals in the length of the fabric so as to provide tuft loops, the loops in adjacent cords being substantially aligned transversely of the fabric, said attachment comprising, in combination, guide means mounted on the loom and extending across the fabric, a cutting device mounted on said guide means for reciprocation lengthwise of said guide means and across said loops to engage and sever the latter, said cutting device comprising a pair of rotatable cutting blades, a pair of shoes dimensioned to pass within and through said loops, each shoe being positioned adjacent and beneath one of said blades to guide the blades into cutting engagement with the loops, the blades and their respective shoes being spaced lengthwise of the fabric for concurrent engagement with the loops in each of

two transverse rows of loops, and a motor for rotating said blades, and means operable in timed relation with said loom for energizing said motor to propel said cutting devices on said guide means in one direction, and, after advance of the fabric through a distance corresponding to the spacing between adjacent rows of tuft loops, to propel said cutting device lengthwise of said guide means in the other direction, whereby said loops are successively engaged and severed by said cutting blades on movement of said cutting device across the fabric in each direction to form the tufts.

4. An attachment for a loom on which is woven a fabric having tuft cords lying parallel to the fabric warp, said cords being woven in the fabric at spaced intervals in the length of the fabric so as to provide tuft loops, the loops in adjacent cords being substantially aligned in rows transversely of the fabric, said attachment comprising, in combination, guide means mounted on the loom and extending across the fabric, a cutting device mounted on said guide means for reciprocation lengthwise of said guide means and across said loops to engage and sever the latter, and means operable in timed relation with said loom for propelling said cutting device on said guide means in one direction, and, after advance of the fabric through a distance corresponding to the spacing between adjacent rows of tuft loops, to propel said cutting device lengthwise of said guide means in the other direction, whereby said loops are severed to form a tufted fabric, said cutting device comprising a pair of shoes dimensioned and shaped to pass between said tuft loops and said fabric, a cutting blade positioned adjacent each shoe for engaging and cutting said loops while the associated shoe is passing between the loop to be cut and the fabric, the blades and the respective shoes being spaced lengthwise of the fabric for concurrent engagement with the loops in each of two transverse rows of loops, a common support for said shoes and said blades, and means mounting said support for displacement lengthwise of said fabric, whereby said shoes may guide said blades into the correct position for the severing of the loops on movement of said cutting device across the fabric in each direction.

5. In the method of forming a tufted fabric by weaving into the fabric, at spaced intervals in the length thereof, a plurality of tuft cords extending lengthwise of the fabric, so as to provide tuft loops, the loops in adjacent cords being substantially aligned in rows transversely of the fabric, the step which comprises severing a row of tuft loops while the fabric is under lateral tension, by moving concurrently a pair of cutting edges transversely of the fabric while retaining the same in such spaced relation, measured lengthwise of the fabric, that the respective cutting edges are caused to engage and cut loops in adjacent transverse rows of loops, beginning each cutting stroke at a point inward of the adjacent selvage and beyond at least one tuft cord, and continuing the stroke to the far selvage, and advancing the fabric by substantially the distance between adjacent transverse rows of loops intermediate successive cutting strokes.

6. In the method of forming a tufted fabric by weaving into the fabric, at spaced intervals in the length thereof, a plurality of tuft cords extending lengthwise of the fabric, so as to provide tuft loops, the loops in adjacent cords being substantially aligned in rows transversely of the fabric, the step which comprises severing a row

of tuft loops while the fabric is under lateral tension, by moving concurrently a pair of cutting edges transversely of the fabric while retaining the same in such spaced relation, measured lengthwise of the fabric, that the respective cutting edges are caused to engage and cut loops in adjacent transverse rows of loops, beginning each cutting stroke at a point inward of the adjacent selvage and beyond at least one tuft cord, and continuing the stroke to the far selvage, and advancing the fabric by substantially the distance between adjacent transverse rows of loops intermediate successive cutting strokes, and concurrently and during the severing of loops adjacent the selvages, displacing the cutting edges in the direction of distortion of the fabric caused by lateral tensioning of the fabric to compensate for such distortion.

7. In the method of forming a tufted fabric by weaving into the fabric, at spaced intervals in the length thereof, a plurality of tuft cords extending lengthwise of the fabric, so as to provide tuft loops, the loops in adjacent cords being substantially aligned in rows transversely of the fabric, the steps which comprise severing a row of tuft loops while the fabric is under lateral tension, by moving a pair of cutting edges, while in respective alignment with adjacent transverse rows of loops, from a point substantially inward of a first selvage to the second selvage, advancing the fabric relative to the cutting edges by a distance corresponding to the spacing between adjacent transverse rows of loops, and thereafter moving the cutting edges in the opposite direction, from a point substantially inward of the second selvage to the first selvage.

8. An attachment for a loom on which is woven a fabric having tuft cords extending lengthwise of the fabric, said cords being woven in the fabric at spaced intervals in the length of the fabric so as to provide tuft loops, the loops in adjacent cords being substantially aligned transversely of the fabric, said attachment comprising, in combination, guide means mounted on the loom and extending across the fabric, a cutting device mounted on said guide means for reciprocation lengthwise of said guide means and across said loops to engage and sever the latter, said cutting device comprising a pair of rotatable cutting blades, a pair of shoes dimensioned to pass within and through said loops, each shoe being positioned adjacent and beneath one of said blades to guide the blades into cutting engagement with the loops, the blades and their respective shoes being spaced lengthwise of the fabric for concurrent engagement with the loops in two adjacent transverse rows of loops, and a motor for rotating said blades, means operable in timed relation with said loom for energizing said motor to effect reciprocation of said cutting device on said guide means, whereby said loops are successively engaged and severed by said cutting blades to form the tufts, and means terminating movement in each direction of said cutting device in a position such that said shoes extend inwardly beyond the outermost tuft cords, whereby such cords are not engaged and severed by said blades on the succeeding cutting stroke.

9. An attachment for a loom on which is woven a fabric having tuft cords lying parallel to the fabric warp, said cords being woven in the fabric at spaced intervals in the length of the fabric so as to provide tuft loops, the loops in adjacent cords being substantially aligned in rows transversely of the fabric, said attachment comprising,

in combination, guide means mounted on the loom and extending across the fabric, a cutting device mounted on said guide means for reciprocation lengthwise of said guide means and across said loops to engage and sever the latter, and means operable in timed relation with said loom for effecting reciprocation of said cutting device on said guide means, whereby said loops are severed to form a tufted fabric, said cutting device comprising a pair of shoes dimensioned and shaped to pass between said tuft loops and said fabric, a cutting blade positioned adjacent each shoe for engaging and cutting said loops while the associated shoe is passing between the loop to be cut and the fabric, and means for retaining said cutting devices, immediately prior to each cutting stroke, in a position such that the next adjacent uncut row of loops passes beneath the rearward shoe, so that the first few loops in each row remain uncut by the rearward of said cutting blades.

10. In a method of forming a tufted fabric by weaving into the fabric, at spaced intervals in the length thereof, a plurality of tuft cords extending lengthwise of the fabric, so as to provide tuft loops, the loops in adjacent cords being substantially aligned in rows transversely of the fabric, the steps which comprise severing a row

5
10
